KEY HOLDER

Henry A. Gallagher, Los Angeles, Calif.

Application April 26, 1949, Serial No. 89,666

10 Claims. (Cl. 70—456)

1

This invention has to do with a key holder and it is a general object of the invention to provide a key holder which serves to effectively and conveniently carry one or more keys such as the average person carries in a pocket or purse, and which is of simple, inexpensive construction, is neat and compact, and is free of complicated, delicate, or costly mechanisms subject to failure or improper operation.

The device of the present invention is characterized by a sectional body which defines a longitudinal guideway open at one or both ends of the body and a chamber within the body communicating with the guideway. Keys are engaged in either or both ends of the guideway and an ejecting spring is under compression between the heads on the inner ends of the key while stops in the body limit outward movement of the keys under the action of the ejecting spring. A lock means is provided in connection with each key and involves a spring held lock pin that directly engages or cooperates with the key and positively holds the key either in an in position where it is within the body or an out position, where it projects from the body, the lock pin being disposed transversely of the body and having an end accessible at the exterior of the body so that it is subject to being conveniently depressed to release the key to move either in or out.

It is a general object of the present invention to provide a key holder of the general character referred to in which there is a rigid elongate body with an opening continuously through it from one end to the other and in which keys are carried in the end portions of the guideways and have a compression spring located between them normally yieldingly urging both keys outwardly.

Another object of the invention is to provide a structure of the general character referred to wherein the keys employed are of simple, inexpensive construction or formation. The key of the present invention may have a conventional shank with a straight plain back and with a front that it suitably profiled while a simple, small head is provided at the inner end of the shank serving to slidably support the key in the body. In the preferred construction the straight, plain back of the key is continuous throughout the length of the key and has notches which cooperate with the lock bolt or pin of the structure.

Another object of the invention is to provide a holder of the general character referred to wherein a key slidably mounted in a body is directly engaged by a spring held lock pin which is operable from the exterior of the body. In the preferred arrangement one end of the lock pin projects from the exterior of the body to

be conveniently accessible so that it can be depressed to release the key while the body is held in the hand of the user.

A further object of the invention is to provide a key holder of the general character referred to which involves but few simple, inexpensive parts which make for dependable convenient operation and for a practical inexpensive construction.

The various objects and features of my invention will be fully understood from the following detailed description of typical preferred forms and applications of the invention, throughout which description reference is made to the accompanying drawings, in which:

Fig. 1 is a perspective view of a typical embodiment of the present invention showing it with the several keys in or retracted, making the structure suitable for carrying in a pocket or a purse or the like. Fig. 2 is a view similar to Fig. 1, showing a key ejected or extending from one end of the body and in position ready for engagement with a lock. Fig. 3 is an enlarged end elevation of the structure shown in Fig. 1. Fig. 4 is a view similar to Fig. 3 showing a construction wherein the body has a single guideway instead of having two guideways, as shown in Fig. 3. Fig. 5 is a side elevation of a key provided by the present invention. Fig. 6 is an enlarged detailed sectional view taken longitudinally of the structure, as indicated by line 6—6 on Fig. 4. Fig. 7 is a longitudinal sectional view of the structure taken as indicated by line 7—7 on Fig. 6. Fig. 8 is a view similar to Fig. 6, showing a key ejected or extended, ready for operation. Fig. 9 is an enlarged detailed transverse sectional view taken as indicated by line 9—9 on Fig. 8, and showing the lock pin engaged with and holding the key. Fig. 10 is a view similar to Fig. 9 showing the lock pin operated so that the key is released. Fig. 11 is an enlarged detailed sectional view taken as indicated by line 11—11 on Fig. 8. Fig. 12 is a view similar to Fig. 6 showing a somewhat different form of the invention. Fig. 13 is a sectional view taken as indicated by line 13—13 on Fig. 12. Fig. 14 is a view of a portion of Fig. 12 showing the key ejected or in an operating position. Fig. 15 is a sectional view taken as indicated by line 15—15 on Fig. 13. Fig. 16 is an enlarged detailed transverse sectional view taken as indicated by line 16—16 on Fig. 12. Fig. 17 is an enlarged detailed sectional view taken as indicated by line 17—17 on Fig. 12 and Fig. 18 is an enlarged detailed sectional view taken as indicated by line 18—18 on Fig. 12.

The structure provided by the present invention involves, generally, a body A which is preferably sectional in construction and defines a longitudinal guideway 10 with a chamber por-

tion 11 intermediate the ends of the body, one or more keys B slidably supported in the guideway 10 to be independently operable therein between in or retracted positions, as shown in Fig. 6, and out or operating positions as shown in Fig. 8, ejecting means C acting to normally yieldingly urge the keys outwardly or to the position shown in Fig. 8, stop means D serving to limit outward movement of the keys and lock means E releasably holding the keys in the said positions.

The body A is preferably a simple elongate structure that may be substantially rectangular in cross sectional configuration. In the preferred form of the invention the body is of sectional construction and defines one or more guideways 10 which extend longitudinally of the body, preferably from one end to the other thereof. Figs. 1 to 4 of the drawings will serve to illustrate how the body can be constructed to have one guideway 10 or more than one guideway, as circumstances require.

In the preferred construction the body A has a main section 12 with an opening or channel in its inner side 13, which channel forms the guideway 10 for carrying one or more keys B. Another or second section of the body is a closure section releasably secured to the side 13 of section 12 to form a closure for the guideway 10 so that the key or keys are retained therein. In the form of the invention illustrated in Figs. 1, 2 and 3 of the drawings, the closure section 14 of the body is a simple, flat, thin plate-like part secured to the flat side 13 of section 12, and in this case there is a second main section 12 and the closure section 14 is retained or interposed between the two main sections 12 to the end that a sectional closure section 14 forms a closure for the guideways of the two main sections 12. In the form of the invention shown in Fig. 4 the closure section 14a together with the main section 12 completes the body A and in such case it is desirable that the closure section be somewhat thicker than that shown in Fig. 3 and that its outer side or face 15 be finished or surfaced or even ornamented to correspond to the outer face 16 of the main section 12. For simplicity of illustration the simple form of body which defines a single guideway 10 is shown in the various figures of the drawings following Fig. 4, it being understood, however, that if desired the type of construction shown in Figs. 1 to 3 may be employed in carrying out or in connection with the various details of construction illustrated in Figs. 4 to 18, inclusive.

The body A includes, in addition to the sections which cooperate to define the guideway or guideways, a fastening means by which the body sections are secured together. In practice it is preferred to employ a releasable fastening means and as shown in the drawings the fastening means may include a plurality of screw fasteners 20 suitably located throughout the body construction so that they releasably secure the body sections together without in any way interfering with the construction or functioning of the various other elements of the structure.

Since the structure of the present invention is such that it may carry one or more keys and since the several keys when more than one is employed may be alike in general construction, I will describe but one key, it being understood that the description is applicable to any and all keys included in the device.

The key B, as provided by the present inven-

tion and as illustrated in Fig. 5 of the drawings, involves a usual or typical key shank 21 preferably provided with a straight plain back edge 22 and with a lock operating or profiled front edge 23. A head 24 is provided or formed on the inner end of the shank and has straight parallel edges 25 and 26 and an end 27. The edge 25 of the head is preferably straight and continuous with the back edge 22 of the shank so that it is, in effect, a part or continuation thereof. In accordance with the invention and for cooperation with the means E as will be hereinafter described, the key B is provided with features or characteristics such, for example, as one or more notches 30 in the straight back edge 22. In the preferred form of the invention there is a notch 30 in the edge 22 at the head end portion thereof and there is a like or similar notch 31 in the edge 22 in the outer or forward end portion thereof.

The ejecting means C, in accordance with the present invention, is preferably a simple compression spring carried in the chamber portion 11 of the opening defined by the body A. The inner end or head 24 of each key is engaged by a spring of means C to the end that each key is normally yieldingly urged outwardly so that it moves to an extended or operating position as shown in Figs. 2 and 8 of the drawings whenever released through operation of the lock means E. In the usual application of the invention two keys B are carried in the guideway 10, the keys being entered in the guideway from opposite ends thereof so that their heads 24 are opposed and spaced apart in the body as clearly shown in Figs. 6 and 7 of the drawings. In such case the spring 35 of the ejecting means C is arranged under compression between the heads 24 of the two keys in the guideway 10. In practice the spring of the means C may vary in form and construction and for example I have illustrated this spring in Figs. 6, 7, 8 and 11 as a simple coil or helical spring, whereas in Figs. 12, 13 and 14 the spring 35a is illustrated as a flat spring of zigzag formation so that it corresponds, generally, in cross section to the cross sectional configuration of the chamber portion 11 of the guideway.

The stop means D provided for or in connection with each key B serves to limit outward movement of the key in the body or in the guideway of the body and stops the key in an ejected or out position where the shank portion 21 thereof projects from the body in a manner to enter a lock, as clearly illustrated in Figs. 2, 8 and 14 of the drawings.

In the form of the invention illustrated on sheet 1 of the drawings the stop means D involves an inwardly facing stop shoulder 40 in the body or in the guideway of the body so positioned as to be engaged by the forward end 41 of the head of the key. In this particular form of the invention the stop 40 is a fixed or permanent stop, being formed or established permanently in the body by so shaping the guideway as to provide the desired stop shoulder. In the form of the invention shown on sheet 2 of the drawings the stop shoulder 40a instead of being a fixed permanent or rigid part of the body is formed on an element 44 which is shiftable in or relative to the body so that the shoulder can be disengaged from the key permitting the key to be removed from the body, if desired, for changing, repair, replacement, or other handling of the key independent of the body. In this form of the invention the member 44 is shown as a leaf

spring secured in the body as by fastening means 42 and carried in a recess 43 in the body communicating with the guideway. The stop shoulder 40^a, like the stop shoulder 40 shown on Sheet 1, cooperates with the forward end 41 of the head of the key. The member or spring 44 has a part 45 extending outward or forward from the shoulder to be accessible to an implement inserted in the end portion of the guideway so that the spring can be depressed to move the shoulder 40^a to a position where it will not stop the key.

The lock means E serves or acts to releasably hold the key in either the in or retracted position shown in Fig. 6 or in the out or working position shown in Fig. 8. The lock means in its preferred form involves a lock bolt or pin 50 slidably carried in an opening 51 in the body and a spring 52 which engages or acts upon the pin to normally yieldably hold it in a position where it enters a notch of the key to positively prevent shifting of the key lengthwise of the guideway. In the preferred arrangement the opening 51 carrying the lock pin extends transversely of the body and is near one end of the body where it is so located as to intersect the guideway 10 at one edge thereof, preferably at the edge which is engaged by the back edge 22 of the key. In the form of the invention shown on Sheet 1 of the drawings the lock pin has a key engaging portion 55 slidably carried in the guideway 51, which portion is round in cross section and is shiftable into and out of engagement with the key as the lock pin is operated. When the lock pin is in the set or operating position as shown in Fig. 9 of the drawings the part 55 of the pin is in a notch of the key, either notch 30 or notch 31, and thus positively holds the key against movement relative to the body. When the lock pin is operated or depressed, as shown in Fig. 10, the part 50 is removed from the key to be free of or out of the notch of the key, thus leaving the key free to move between the positions shown in Figs. 6 and 8 of the drawings. The body may be provided with guideways 51^b to receive and guide the pins 50 when the form of the invention shown in Figs. 1 to 3 is employed.

In the particular case shown on Sheet 1 of the drawings the lock pin has a stem portion 56 of reduced diameter that projects from the key engaging part 55 and is slidably carried in a portion 51^a of the body opening. A cup-like cap or button 57 is carried on the outer end of the stem and is slidably engaged in an enlargement 58 of the opening in the body. The cap carries or houses a spring 59 which forms the means 52, the spring being so arranged on the stem 56 and in the cap 57 as to normally yieldingly hold the lock pin in the operating position shown in Fig. 9. When the lock pin is in the position shown in Fig. 9 the cup-like cap 57 projects from the exterior of the body to be conveniently accessible so that the user to release the key for movement merely depresses the cap or button to a position where it is flush with the exterior of the body, as shown in Fig. 10.

In the form of the invention shown on Sheet 2 of the drawings the lock pin 50^a is similar, generally, to the lock pin above described in that it has the key engaging part 55, stem 56 and a cap 57 carried by the stem. In this form of the invention, however, the means or spring 52 that operates the lock pin is not a helical spring carried in the cap 57 but rather is a leaf spring 60 mounted in a recess 61 extending longitudinally in the body. The leaf spring is anchored

5
10
15
20
25
30
35
40

or secured at 62 and its free or working end is forked and engages a reduced part 65 of the stem 56 as clearly shown in Fig. 17 of the drawings. In this form of the invention a single leaf spring 60 may be anchored midway between the ends of the body A so that it has like oppositely projecting end portions engaging and operating lock pins at the two ends of the body.

From the foregoing description it is to be observed that through my present invention the body A is of very simple, inexpensive, construction and it is such that exterior surfaces thereof may be suitably ornamented or may be employed to carry initials or other identification or even advertising matter. Further, it is apparent that various features such as bodies of luminous paint 80 or the like may be applied to the body as at the end portions thereof, as may be desired. The key employed in carrying out the present invention is of simple form, easily manufactured and involves a minimum amount of material. A feature of the invention is that the key formation required for the present construction can be gained by suitably modifying the ordinary or average key by simply modifying the head end thereof and notching the straight back, all as shown in Fig. 5 of the drawings. The ejecting means C of the present invention requires but a single spring to operate two keys and it will be apparent from the drawings that the spring required may be of simple, inexpensive, construction. The lock means which is a feature of the present invention involves a minimum of parts, there being but a single lock pin and its operating spring required to lock a key and the arrangement is such that the lock pin directly engages the key, thus eliminating complicated, delicate, expensive, intervening parts such as are generally involved in structures of this general character. The lock means of the present invention is easily operated, is conveniently located, and serves to securely hold the key either in or out, as required.

When the key or keys are in, as shown in Figs. 1 and 6 of the drawings, the structure is compact and suitable for carrying either in a purse or in a pocket, whereas when a key is desired for use it is merely necessary to depress the lock pin, holding the key, whereupon the key moves to operating position where it is secured by releasing the lock pin. When the key has been used and it is desired to restore the key to the in position it is merely necessary to release the lock pin and press the key into the body releasing the lock pin so that it holds the key in the in position.

Having described only typical preferred forms and applications of my invention, I do not wish to be limited or restricted to the specific details herein set forth, but wish to reserve to myself any variations or modifications that may appear to those skilled in the art and fall within the scope of the following claims.

Having described my invention, I claim:

1. A key holder including, an elongate body having a main section with a guideway in one side open at each end of the body and a closure section at said side of the main section closing the guideway, two keys slidably carried in the guideway, a single spring in the guideway between the keys normally urging the keys outwardly in the guideway, and lock means for each key releasably holding it in the body or projecting from one end of the body.

2. A key holder including, an elongate body

75

with a longitudinal guideway open at one end of the body, a key slidably carried in the guideway to reciprocate between an in position wholly within the body and a working position projecting from the end of the body parallel therewith, a spring in the body normally yieldingly urging the key to the working position, stop means stopping the key in working position, and lock means releasably holding the key in said position, the stop means including a spring carried by the body and having a stop shoulder engaged by the key.

3. A key holder including, an elongate body with a longitudinal guideway open at one end of the body, a key having an outer working end and an inner end slidably carried in the guideway to reciprocate between an in position wholly within the body and a working position where the working end of the key projects from the end of the body parallel therewith, a spring in the body normally yieldingly urging the key to the working position, releasable stop means stopping the key in working position and including a member carried by the body and shiftably relative thereto, said member having a normal working position where it is engaged by the inner end of the key upon the key being moved to working position, and lock means releasably holding the key in said positions.

4. A holder for a key having a head and a straight longitudinal notched back edge including, an elongate body having a longitudinal guideway adapted to slidably carry the key, a spring in the guideway adapted to normally urge the key outwardly in the guideway to project from one end of the body, a releasable stop means adapted to limit outward movement of the key in the guideway including, a leaf spring carried in the body and having a stop shoulder adapted to be engaged by the head of the key when the key is in working position, and a lock pin shiftably carried in the body and adapted to releasably engage the notches in the key to hold the key in said working position or in an in position where it is wholly within the body.

5. A key holder including an elongate body with a longitudinal keyway therein open at each end of the body, two keys arranged oppositely and slidably carried in the keyway, the keys having opposed heads slidably engaged in the keyway, a single spring in the keyway under compression between the heads of the keys and normally yieldingly urging each of the keys to a working position where it projects from the body, and lock means releasably holding the keys in retracted positions where they are wholly within the body.

6. In combination, an elongate body having a guideway extending longitudinally therethrough and open at the ends of the body, two oppositely disposed keys slidably supported in the guideway, each key having an edge with notches thereon, spring means normally yieldingly urging the keys apart, a lock pin for each key being shiftably carried by the body and adapted to move into and out of engagement with a notch of the key, and a single leaf spring carried by the body and extending longitudinally thereof and engaging each lock pin to normally yieldingly hold it in notch engaging position.

7. In combination, an elongate body having a guideway extending longitudinally therethrough and open at the ends of the body, two oppositely disposed keys slidably supported in the guideway, each key having an edge with notches therein, a single spring in the guideway between the op-

posed ends of the keys normally yieldingly urging the keys apart, a lock pin for each key carried by the body to move into and out of engagement with a notch of the key, and a single leaf spring carried by the body and extending longitudinally thereof and engaging each lock pin to normally yieldingly hold it in notch engaging position.

8. In combination, an elongate body having a guideway extending longitudinally therethrough and open at the ends of the body, two oppositely disposed keys slidably supported in the guideway, each key having an edge with notches therein, spring means normally yieldingly urging the keys apart, a lock pin for each key carried by the body to move into and out of engagement with a notch of the key, spring means normally yieldingly holding the pins engaged in the notches of the keys, and stop means limiting outward movement of the keys in the guideway including a single elongate leaf spring carried by the body to extend longitudinally thereof and having stop shoulders at its ends cooperatively engaged by the keys.

9. In combination, an elongate body having a guideway extending longitudinally therethrough and open at the ends of the body, two oppositely disposed keys slidably supported in the guideway, each key having an edge with notches therein, spring means normally yieldingly urging the keys apart, a lock pin for each key carried by the body to move into and out of engagement with a notch of the key, a single leaf spring carried by the body and extending longitudinally thereof and engaging each lock pin to normally yieldingly hold it in notch engaging position, and stop means limiting outward movement of the keys in the guideway including a single elongate leaf spring carried by the body to extend longitudinally thereof and having stop shoulders at its ends cooperatively engaged by the keys.

10. In combination, an elongate body having a guideway extending longitudinally therethrough and open at the ends of the body, two oppositely disposed keys slidably supported in the guideway, each key having an edge with notches therein, a single spring in the guideway between the opposed ends of the keys normally yieldingly urging the keys apart, a lock pin for each key carried by the body to move into and out of engagement with a notch of the key, a single leaf spring carried by the body and extending longitudinally thereof and engaging each lock pin to normally yieldingly hold it in notch engaging position, and stop means limiting outward movement of the keys in the guideway including a single elongate leaf spring carried by the body to extend longitudinally thereof and having stop shoulders at its ends cooperatively engaged by the keys.
